United States Patent Office.

JOHN H. SMITH, OF ENFIELD, ASSIGNOR TO HARTFORD CARPET COMPANY, OF HARTFORD, CONNECTICUT.

Design No. 4,956, dated May 30, 1871.

DESIGN FOR A CARPET-PATTERN.

The Schedule referred to in these Letters Patent and making part of the same.

all whom it may concern:

I, JOHN H. SMITH, of the town of Enfield, county of Hartford and State of Connecticut, have invented or produced a new and original design for a Pattern to be Inwrought into Ingrain or other Carpeting in colors similar to those painted or otherwise represented in the drawings or photographs accompanying this specification, or in other colors substituted in the place of those painted on the drawings or photographs with; and I do hereby declare that the drawings or photographs accompanying this specification do give and convey, to one skilled in the art of carpet-weaving, a detailed and thorough description of the nature of my invention, and are sufficient to enable any one skilled in the art of carpet-weaving to use my invention.

What I claim as my invention, and desire to secure by Letters Patent, is—

The configuration of the design hereunto annexed when applied to carpeting in the form similar to the drawings or photographs accompanying this specification.

J. H. SMITH.
